UNITED STATES PATENT OFFICE.

COLONEL A. MURPHY, OF CHICAGO, ILLINOIS.

NEEDLE-THREADER.

No. 875,725.

Specification of Letters Patent.

Patented Jan. 7, 1908.

Application filed February 27, 1907. Serial No. 359,564.

To all whom it may concern:

Be it known that I, COLONEL A. MURPHY, citizen of the United States, residing at Chicago, in the county of Cook and State of Illinois, have invented certain new and useful Improvements in Needle-Threaders, of which the following is a specification.

My invention relates to improvement in needle threaders, and the objects of my invention are, first, to provide a portable threader adapted to thread a needle having an eye near the point thereof, such as a sewing machine needle; and, second, the provision of an improved threader at low initial cost, practical in operation, for the purpose of threading any sewing instrument.

With the above and other objects in view, this invention consists of the novel features and the combination and arrangement of parts hereinafter more specifically described, illustrated in the drawings, and particularly pointed out in the claims hereunto appended.

In describing the invention in detail reference is had to the accompanying drawings forming a part of this specification wherein like numerals of reference indicate corresponding parts throughout the several views, and in which

Figure 1 is a side elevation of a threader for an ordinary sewing needle, in which the eye is near the heel of the needle. Fig. 2 is a side elevation of a threader for a sewing-machine needle, in which the eye is near the point of the needle. Fig. 3 is an enlarged section on line 3—3 of Fig. 1. Fig. 4 is an enlarged section on line 4—4 of Fig. 2. Fig. 5 is an enlarged central longitudinal section showing ordinary needle in position on the threading member. Fig. 6 is an enlarged end elevation of a threader for an ordinary needle. Fig. 7 is a top plan view of a threader for a sewing-machine needle, and Fig. 8 is a view of a blank as it comes from the die, one end partly broken away.

One embodiment of my invention will now be described. The body portion, 9, may be made in any desired manner, and of any suitable material. Preferably the portion 9 is made from thin sheet metal by the use of a die and folded to have two thicknesses of the material to afford lightness and strength. For the purpose of providing a needle receiving groove and a needle stop one end of the blank shown in Fig. 8 (that is to say parts 13, 13 and 11) is formed as shown in Fig. 7, the part 11 being formed with the side walls suffi-

ciently apart to accommodate the thickness of needle to be threaded and constitute a needle stop, and the parts 13, 13 being formed sufficiently apart to serve as guide-arms upon either side of a needle to be threaded. The main purpose of the guide-arms is to cause the threader to approach the needle substantially parallel with the free end of the threading member, 10, and its hook, it being understood that the eye of a sewing needle is elongated axially of the needle. The threading member, 10, is provided with the usual hook at its free end for the purpose of grasping the thread and carrying the same through the eye of the needle as the member is withdrawn. The chief purpose of the stop, 11, is to limit the movement of the threader relatively to the needle to a position to register the threading member with the eye of the needle.

The threading member, 10, is made of steel wire small enough to readily pass through the eye of the needle after a suitable hook is formed on the free end of the member. The position in which the member 10 is fastened in the end of the body 9 will depend upon the distance from the stop 11 to the center of the eye of the needle, which will vary with size and kind of needles, and whether the eye is near the heel or the point of the needle. The member 10 may be secured in place in any suitable or desired manner. I have shown a perforation, 14, and have extended the stem of the member back past such perforation and filled the hole, 14, with solder, thus fastening the member. The body portion, 9, preferably is flat and elongated and is transversely slotted or suitably cut away at one end, as at 15, to receive the thread. In Fig. 1 I have a V-shaped slot, but do not wish to be limited to any particular form of slot. Preferably the slot 15 is given a form that will facilitate the prompt movement of the thread, 17, to a position before the hook of member 10 that the latter may be withdrawn from the eye of the needle, 16. It will be noted that the threader is open at one end and may be advanced to the needle at right angle therewith. It will be noticed I employ guide-arms 13, 13 sufficiently apart to serve as guides but not to offer resistance to advance of the threader upon the needle.

In manufacture, the distance from the point of a sewing-machine needle to the center of the eye is predetermined and the member 10 set so that it is only necessary to

place the point of the needle against the stop 11 and gently advance the thresher toward the needle when the member 10 and its hook will pass through the eye. The thread is 5 then drawn into the slot, 15, which, in form, is adapted to direct the thread to a position to be grasped by the hook when the member 10 is withdrawn from the eye. In the case of an ordinary needle, the heel, instead of the 10 point, is caused to rest against the stop, with the guide-arms on either side of the needle. It will be apparent this may be accomplished by taking the form shown in Fig. 2 in the 15 right hand and advancing the thresher to the left until the needle is between the guide-arms 13, 13, then raising the thresher until the stop is up against the point of the needle, when the member 10 will register with the eye of the needle and may be pushed or extended 20 therethrough to grasp the thread and the two be withdrawn in the act of moving the thresher to the right.

Having thus fully described my invention, what I claim as new, and desire to secure by 25 Letters-Patent, is—

1. In a sewing machine needle thresher, the combination of an elongated body portion having one end transversely slotted to receive the thread, an immovable threading 30 member extending longitudinally of said body portion, and a stop at the bottom of the body portion to limit the movement of the thresher to a position to register the threading member with the eye of the needle, substantially as shown and described.

2. In a sewing machine needle thresher, the combination of an elongated body portion having one end transversely slotted, an immovable threading member extending

longitudinally of said body portion, a stop 40 at the bottom of the body portion to limit the movement of the thresher to a position to register the threading member with the eye of the needle, and a guide-arm, substantially as shown and described. 45

3. In a sewing machine needle thresher, the combination of an elongated body portion having one end transversely slotted, an immovable threading member extending longitudinally of said body portion, a stop at 50 the bottom of the body portion to limit the movement of the thresher to a position to register the threading member with the eye of the needle, and approximately parallel guide-arms to keep the needle substantially 55 parallel with the free end of the threading member and its hook, substantially as shown and described.

4. In a sewing machine needle thresher, the combination of a flat elongated body 60 portion having one end transversely slotted, an immovable threading member extending longitudinally of said body portion, a stop at the bottom of the body portion to limit the movement of the thresher to a position to 65 register the threading member with the eye of the needle, and approximately parallel guide-arms to keep the needle substantially parallel with the free end of the threading member and its hook, substantially as shown 70 and described.

In witness whereof I affix my signature in presence of two witnesses.

COLONEL A. MURPHY.
